UNITED STATES PATENT OFFICE

110,421

DESIGN FOR A SHIRT

Beatrice Melville, Long Beach, N. Y.

Application June 8, 1938, Serial No. 77,663

Term of patent 3½ years

To all whom it may concern:

Be it known that I, Beatrice Melville, a citizen of the United States of America, residing in Long Beach, county of Nassau, and State of New York, have invented a new, original, and ornamental Design for a Shirt, of which the following is a specification, reference being had to the accompanying drawings, forming part thereof, wherein,

I claim:

The ornamental design for a shirt, substantially as shown.

BEATRICE MELVILLE.
